PERFORATED CONICAL DYE TUBE FOR THE
WINDING OF TEXTILE THREADS

Boudewijn Remi Jan Steverlynck, Courtrai, Belgium, assignor to "Groeninghe Vervenij P. V. B. A." (Société de Personnes à Responsabilité Limitée), Courtrai, Belgium

Application March 5, 1951, Serial No. 213,856

Claims priority, application Belgium
March 6, 1950

6 Claims. (Cl. 242—118)

1
Conical or cylindrical perforated dye tubes made of metal or specially impregnated paper adapted for winding textile threads, intended for bleaching, dyeing and the like yarns in packages are used since a long time.

Nowadays, the thread spools or cheese are executed in such a manner that the two ends of the tube remain free for instance over about 1 cm., because in order to avoid the risk of some threads projecting beyond the base of the conical tube and being damaged during subsequent handling.

When it is desired to bleach or dye conical cheeses they are fitted over a carrier of the treating machine. Such carriers include a three or four rib spindle or a perforated dye tube allowing the passage of liquids through the superposed package system thus formed. This cheese system or upright column communicates with the openings provided in the double bottom of the circulation machine.

It is, however, necessary to insert between the successive conical cheeses an intermediary spacer or inset acting as a packing between said cheese. This spacer is for instance a round corrugated plate provided in its center with an opening adapted to be fitted on the spindle in the same manner as the cheeses over the machine carrier. The corrugations of the inset washer match through one surface the small diameter of a conical dye tube and through its outer surface the larger diameter of such a tube. Without such spacers, the wider end of one conical dye tube would engage the cotton threads on the next and risk cutting the latter or staining them through such a localized pressure.

The use of insets leads, however, to a supplementary operation and implies the drawback that the workman or the apprentice may inadvertently lay said insets upside down. On the other hand, as the ends of said conical tubes may become damaged through wear, this results also in a lack of fluidtightness between the tubes and the insets.

The present invention has for its object to make such insets unnecessary while avoiding the above mentioned drawbacks. To this end, the larger base of the perforated conical type is provided with an outer thicker sectional flange which allows winding the threads up to the extreme end of the tube without any risk of the threads projecting beyond the base of the perforated tube.

This thickened wall section or flange may be constituted by a ring welded over the outside of

the cone along the periphery of its larger base but it could also be made through other means, e. g. by folding the end of the cone outwardly.

A further important feature consists in providing, in addition to the outer extra thickness of the tube, an inner ring-shaped flange which may be shaped through stamping to form a ring engaging the outwardly folded end of the perforated conical dye tube.

Accompanying drawings show by way of example and by no means in a limiting sense how the invention may be practically executed.

In said drawings,

Fig. 1 is a perspective view of a conical dye tube according to our invention.

Figs. 2 and 3 are a perspective view and a partly torn-off sectional view of a modification.

Fig. 4 diagrammatically shows two superposed improved cones.

Fig. 5 relates to a further modification.

Fig. 6 illustrates means for winding thread on the improved conical tubes.

In Fig. 1, 1 designates a perforated metal body forming a conical dye tube that is provided, according to the invention, with a flange, ring or extra thickness 2 along its lower edge defining the larger base of the cone.

This flange may be constituted by a ring welded to the edge of the cone although any other suitable means may be used. This flange or extra thickness thus provides means for winding the thread down to the lower limit of the perforated body of the conical tube without any risk of some threads sliding off the cone and it is, therefore, possible to superpose the conical cheeses over one another in the treating machine without an inset being required between them.

In the embodiment disclosed in Figs. 2 and 3, the lower edge 7 of the tube 11 is bent outwardly and is provided with a flange 2' that is fitted over the bent edge through stamping so as to form the desired extra thickness.

As illustrated in the drawing, the outer flange 2' may be in one with an inner ring or annulus 8 forming an annular flange along the edge of the conical tube.

Said latter ring 8 should have preferably a breadth of five to ten mm. but it is necessary in all cases that it allow the tubular cones to fit, to a sufficient extent, inside one another when the spools or cheese are superposed inside the treating machine. Furthermore, this ring 8 is provided advantageously with small apertures 9, the number of which is for instance six, said openings being adapted to further the passage

of the treating liquid in order to cut out any possibility of the formation of stains on the material during its treatment.

Furthermore, the ring or annulus 8 may be provided along its inner edge with a fold 19 directed towards the apex of the cone.

Lastly, it is of advantage to slightly bend the upper edge of the perforated conical tube inwardly, as shown at 11 in Fig. 5, in order to prevent the formation of a cutting edge and to increase the resistance of the tube.

By reason of the presence of the inner flat ring or annulus 8, the larger end of the cone extends through a much lesser length over the end of the underlying cone. Consequently, there is a lesser risk of obtaining undyed parts and there is also a lesser deformation of the upper end of the cheese on which an overlying cone rests directly and uniformly while a more intimate contact is provided between the superposed cheese positioned inside the machine in column formation.

Furthermore, the resistance of the metal conical tubes is increased through this structure which forms an important advantage, especially if one considers that such articles are often taken little care of and easily allowed to drop to the ground.

Finally, the outer flange at the larger end of the conical tube by no means impedes the replacement of the latter by a wooden or cardboard cone, once the package has been dried, before delivering the dried package to the customer, when the metal cones are once more, taken into the operating cycle.

When it is desired to wind yarn over such perforated conical tubes, there is positioned inside the cone a mandrel of wood or the like suitable material made of two parts 3 and 4, as illustrated in Fig. 6, said parts being screwed or fitted inside one another and provided each with an outer flange 5 or 6 projecting outwardly to an extent such as to prevent the terminal flange on the conical tube 1 from damaging the drum on the spooling means.

What I claim is:

1. A perforated conical dye tube for the winding of a textile thread, said tube having a plurality of perforations extending through the wall of the cone for passage of dye liquor therethrough and being provided at its larger end with an outer relatively narrow thread retaining rim adapted to allow the winding of thread on the body of said tube down to its end and having an inwardly extending flat annulus adapted for engagement with the smaller end of a similar tube the said annulus being of a breadth sufficient to limit the penetration of one tube within the other when a plurality of said tubes are disposed in stacked relationship.

2. A dye tube according to claim 1 in which said thread retaining rim consists of an outwardly bent portion of said cone disposed at the larger end thereof and integral therewith.

3. A dye tube according to claim 2 wherein said annulus comprises an inwardly crimped outer peripheral portion engaging said outwardly bent portion of said cone.

4. A dye tube according to claim 1 wherein said annulus has perforations formed therein for the passage of dye liquor therethrough.

5. In combination a dye tube according to claim 1, and a mandrel disposed within said tube, said mandrel having two interengaging portions inserted in said tube from opposite ends thereof engaging said ends and extending outwardly beyond said ends for the protection thereof.

6. A dye tube according to claim 1, wherein the smaller end of said cone comprises a slightly inwardly bent portion.
